(57) **CLAIM**

The ornamental design for a pump mount as shown and described.

DESCRIPTION

FIG. 1 is a first isometric view of a pump mount;

FIG. 2 is a second isometric view of the pump mount;

FIG. 3 is a front elevational view of the pump mount;

FIG. 4 is a left side view of the pump mount;

FIG. 5 is a right side view of the pump mount; and,

FIG. 6 is a bottom plan view of the pump mount.

The broken lines in the figures are for environmental purposes only and form no part of the claimed design.
